United States Patent Office

Des. 182,633
Patented Apr. 22, 1958

182,633

WIRE DRAWING MACHINE

Norman A. Wilson, Worcester, Mass., assignor to Morgan Construction Company, Worcester, Mass., a corporation of Massachusetts

Application September 4, 1956, Serial No. 42,824

Term of patent 14 years

(Cl. D55—1)

FIG. 1.

FIG. 2.

Figure 1 is a perspective view of the wire drawing machine, and

Figure 2 is enlarged fragmentary perspective view of a portion of the machine.

The rear of the machine is substantially plain.

I claim:

The ornamental design for a wire drawing machine, as shown and described.
